(57) **CLAIM**

The ornamental design for figurine, as shown and described.

DESCRIPTION

FIG. 1 is a front perspective view.

FIG. 2 is a front view.

FIG. 3 is a back view.

FIG. 4 is a right side view.

FIG. 5 is a left side view.

FIG. 6 is a top view; and,

FIG. 7 is a bottom view.

The broken line showing of the back, bottom, and arm portions is included for the purpose of illustrating environmental structure and forms no part of the claimed design.

1 Claim, 7 Drawing Sheets# US D635,055 S
